Primary Examiner—Stella M Reid*Assistant Examiner*—Mark A Goodwin*(74) Attorney, Agent, or Firm*—Audrey A. Millemann; Pamela W. Bertani; Weintraub Censle et al.(57) **CLAIM**

The ornamental design for a radial adjuster mechanism for storage and transport devices, as shown and described.

DESCRIPTION

FIG. 1 is a perspective view of a radial adjuster mechanism for storage and transport devices showing our new design.

FIG. 2 is a front view thereof.

FIG. 3 is a rear view thereof.

FIG. 4 is a left view thereof.

FIG. 5 is a right view thereof.

FIG. 6 is a top view thereof.

FIG. 7 is a bottom view thereof; and,

FIG. 8 is a reduced top perspective view thereof, the broken line showing of straps is included for the purpose of illustrating environmental subject matter and forms no part of the claimed design.
